RAILWAY JOURNAL BOX

William F. Triplett, Grand Junction, Colo.

Application December 31, 1947, Serial No. 794,977

2 Claims. (Cl. 308—180)

1

This invention relates to journal box constructions, more particularly to roller bearing journal constructions for railway cars.

The principal object of the invention is to provide a more simplified construction for railway roller bearing journals, which will allow the bearings to be installed without dismantling or rebuilding the truck and which will allow the bearing to be installed in place of the standard bearing brasses of the conventional journal box.

Another object of the invention is to provide a highly efficient oil distributing means for lubricating railway journals of the anti-friction type.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a fragmentary side view of a conventional railway wheel truck illustrating the improved bearing in place therein;

Fig. 2 is a horizontal section taken on the line 2—2, Fig. 1 looking downwardly on the improved bearing;

Fig. 3 is a cross section taken on the line 3—3, Fig. 2 illustrating an end view of the improved bearing;

Fig. 4 is a vertical section taken on the line 4—4, Fig. 1;

Fig. 5 is a detail perspective view illustrating an inner roller bearing race employed in the improved bearing; and

Fig. 6 is a detail perspective view of what will be hereinafter referred to as a load adapter for the improved bearing.

In Fig. 1 a portion of the side frame of a conventional railway wheel truck is indicated at 10 with its bearing boxes at 11. A railway car wheel is indicated at 12 with its axle at 13. The axle 13 terminates in a journal portion 14 terminating in a terminal flange 15. The box 11 is provided with the usual load bearing pad 16.

This invention makes use of the standard box 11, journal 14, and bearing pad 16, and can be used with or without the terminal flange 15. One of the advantages of the improved construction, however, resides in the fact that it may be placed about the journal 14 and within the box 11 without removing the terminal flange 15, and without change in the box.

2

The improved anti-friction railway journal bearing comprises an outer bearing housing block 17 bored internally to form an outer roller race having a medial cylindrical surface for receiving cylindrical roller bearings 18, and two outer conical surfaces for receiving two series of inclined thrust roller bearings 19.

The load rests upon the block 17 through an intermediate adapter block 20, shown more in detail in Fig. 6. The adapter block has an upper semi-cylindrical surface 21 which rests in a downwardly facing, semi-cylindrical concavity in the pad 16. The axis of the cylindrical surface is parallel to the axis of the journal 14. The bottom of the adapter block 20 is flat and rests upon a flat upper surface on the outer bearing housing 17.

The side thrust of the outer bearing housing 17 is absorbed by means of two vertical side rollers 22 which rest in receiving grooves 23 in the two opposite sides of the bearing housing 17. Each side roller 22 is provided with a rocker 24 which extends outward into contact with a side thrust pad 25, with which the conventional boxes 11 are usually provided.

A pivot dowel 26 extends from the outer housing 17 into the adapter block 20 at the middle of the joint. This construction provides a self-aligning bearing, since the housing 17 can rotate about the dowel 26, the rockers 24 rocking on the pads 25. It also provides free sideward movement of the bearing, since the cylindrical surface 21 of the adapter 20 can slide along the concave surface of the pad 16 parallel to the axis of the axle.

A split inner roller race is provided, as shown in Fig. 5, consisting of a first semi-cylindrical inner race section 27, and a second similar inner race section 28. The two race sections 27 and 28 join each other along a zig-zag joining line to form a complete cylindrical inner roller race.

The first section 27 is provided with a pointed tongue 29 which enters a V-shaped receiving notch 30 in the section 28. The second section 28 is similarly provided with a pointed tongue 31 which enters a V-shaped receiving notch 32 at the other side of the first section 27. Each section is provided with a cylindrical inner race 33 for receiving the roller bearings 18, and with conical outer races 34 for receiving the roller bearings 19.

The conical sections 34 are notched and recessed at their opposite extremities, as shown at 35, so that they may dovetail into each other when the two sections 27 and 28 are placed together.

It is desired to call attention to the fact that the roller bearings in rolling from one section onto the other, always overlap both sections simultaneously so as to avoid any bumping or pounding across the joint.

The lower portion of the box 11 is filled with lubricating oil. This oil is lifted and poured into the bearings by two oil scoops 36, there being one scoop secured to the outside face of the section 27, and one secured to the inside face of the section 28. The scoops are preferably formed of sheet metal and are set into receiving mortises in the bearing sections 27 and 28.

The improved bearing is installed by jacking up the side frame 10 and removing the old brasses from the box 11. The two bearing sections 27 and 28 are then placed about the journal 14 behind the terminal flange 15 and temporarily held in place in any desired manner.

The thickness of the inner race sections is sufficient to bring the roller bearings outside the diameter of the terminal flange 15. The inner series of roller bearings 19 and the series of roller bearings 18 are now placed in position, and the outer housing 17, with its adapter 20 in place, is slid thereover. The outer series of rollers 18 is now placed in position and the journal is ready for use.

The above construction provides a self-aligning roller bearing, without requiring any change in the standard journal box or journal.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. An anti-friction journal box construction for railway car journal boxes of the type having a load bearing pad and side thrust pads, comprising

ing: a bearing housing block adapted to surround the journal of a conventional wheel axle; a flat, upper bearing surface on said housing block; a load adapter member having a flat lower surface resting on said flat upper surface; means pivoting said adapter to said block; a semi-cylindrical upper face on said adapter resting in a semi-cylindrical concavity in the journal box pad, the axis of said concavity being parallel to the axis of said journal; a roller mounted at each side of said block to transmit side thrust to the side thrust pads of said box; and anti-friction means within said block supporting said journal therein.

2. An anti-friction journal box construction for railway car journal boxes of the type having a load bearing pad and side thrust pads, comprising: a bearing housing block adapted to surround the journal of a conventional wheel axle; a flat, upper bearing surface on said housing block; a load adapter member having a flat lower surface resting on said flat upper surface; means pivoting said adapter to said block; a semi-cylindrical upper face on said adapter resting in a semi-cylindrical concavity in the journal box pad, the axis of said concavity being parallel to the axis of said journal; a roller mounted at each side of said block to transmit side thrust to the side thrust pads of said box; an inner roller race surrounding said journal; and anti-friction bearing members separating the inner race from said block.
